SUCTION CLEANER BRUSH NOZZLE

Eugene F. Martinec, East Cleveland, Ohio, assignor to Health-Mor, Inc., Chicago, Ill., a corporation of Illinois

Application March 21, 1955, Serial No. 35,136

Term of patent 14 years

(Cl. D9—2)

Fig. 1

Fig. 3

Fig. 1 is a perspective view of a suction cleaner brush nozzle showing my new design.

Figs. 2 and 3 are enlarged side and rear views, respectively, of my new design.

I claim:

The ornamental design for a suction cleaner brush nozzle, substantially as shown.
